UNITED STATES PATENT OFFICE

WENDELL L. CARLSON, OF HADDONFIELD, AND RALPH S. HOLMES, OF HADDON HEIGHTS, NEW JERSEY, ASSIGNEES TO GENERAL ELECTRIC COMPANY, A CORPORATION OF NEW YORK

SIGNAL LIMITING DEVICE

Application filed November 19, 1931. Serial No. 576,116.

Our invention relates to signaling systems and particularly to systems employing high frequency currents, and has for one of its objects to provide an inexpensive means for automatically maintaining the intensity of the signal output of a radio receiving system below a predetermined level without the use of auxiliary equipment.

It is well known that when a high frequency receiving circuit is being adjusted to receive a newly desired frequency, the signals from a powerful or nearby station will often be received with such great volume that the detector is overloaded. This overloading 10 distorts the audio modulation and saturates the amplifier circuits at resonance so as to produce a double peaked tuning characteristic. The volume will be greatly reduced at resonance due to saturation, thus producing 20 an effect similar to reducing the volume by a manual control.

Heretofore means have been provided for limiting or controlling the transmission level in high frequency systems. These means 25 have involved auxiliary tubes which operate as shunt devices which tend to detune a portion of the tuned signaling circuit. Others have involved auxiliary tubes which operate 30 responsively to the intensity of the received high frequency current to impress a variable voltage upon the control element of one or more amplifier tubes to control the amplification of these tubes. Still other means have been provided which develop a potential 35 varying in accordance with the intensity of the varying signal energy received, and apply this potential to a control element of an amplifier tube to eliminate the effects of fading and to maintain the signal output of the receiver below a predetermined level.

Another object of our invention is to provide means for preventing overloading of the detector of radio receivers, which operates 45 without the necessity for auxiliary equipment and which is simple to construct and adjust, and which therefore may be applied to radio receivers without material increase in the cost thereof.

In accordance with our invention, a resistance is connected in the anode-cathode circuit

of a detector to produce a direct current potential which is variable in response to the intensity of the receiver signal current, this potential being supplied to the control element of a preceding tube to limit the output thereof so that the detector tube will not be overloaded.

The novel features which we believe to be characteristic of our invention are set forth with particularity in the appended claims. Our invention itself, however, both as to its organization and method of operation, together with further objects and advantages thereof, will be better understood by reference to the following description taken in connection with the accompany drawing in which Fig. 1 illustrates a preferred embodiment of our invention; and Fig. 2 shows the effect on the output of a detector when the volume becomes excessive.

Referring to Fig. 1 of the drawing, we have illustrated therein two detectors of a superheterodyne type of receiver, with an indication that an intermediate frequency amplifier is interposed between the two detectors. The input circuit 1 is coupled to the grid circuit 2 of an electron discharge device 3. An oscillator circuit 4 is coupled to the circuits 1 and 2, to provide the energy for beating with the incoming signal energy to produce the intermediate frequency by means of the first detector 3. The output circuit 5 of electron discharge device 3 is coupled to the intermediate frequency amplifier (not shown), the output of which is coupled to the grid circuit 6 of the electron discharge device 7 which operates as the second detector or demodulator. The audio output of detector 7 is fed into transformer 8, the secondary of which may be connected to an audio amplifier or a suitable translating device.

For the purpose of developing a source of direct current potential which is variable in response to the intensity of the incoming signal energy, we provide a resistor 9 between the negative terminal of the source of potential for the anodes, and the cathode of device 3; and a resistor 10 in series with resistor 9 and connected between the cathode of de-

vice 3 and the cathode of device 7. A resistor 11, of the type usually provided with power supply units, is shown tapped at an intermediate point to provide a potential for the 5 screen grid electrode of electron discharge device 3.

The operation of this form of our invention is as follows: During normal operation of the circuit when the intensity of the received signal energy is below a certain predetermined level and reception is taking place in the usual way, the potentials developed across the resistors 9 and 10 are of an amount which will allow the detector devices 3 and 7 to operate in a normal way with a normal biasing potential. Assuming that a nearby station for which the manually operated volume control has not been adjusted, is tuned in, or that for some other cause 10 the intensity of the signal energy impressed upon the receiving circuit increases, an increase in the anode current of electron discharge detector 7 takes place, thus increasing the potentials developed across the resistors 15 9 and 10. An increase in the anode current of electron discharge detector 3 also takes place, which increases the potential developed across resistor 9, but the increase in potential due to this anode current increase 20 is of a lesser magnitude than the increase in potential due to the increase in anode current from detector 7 and need not be considered. The increased potential developed by the increase in anode current in the detector 7 25 across resistor 9 further biases the control element of detector 3, thereby reducing the signal energy which is transferred to the intermediate frequency amplifier. This being the case, the signal energy to be amplified by 30 the intermediate frequency amplifier will be greatly decreased and the signal energy impressed upon the detector 7 will not be of a value great enough seriously to overload the circuits. It is important that the potentials 35 supplied to detector 3 initially are adjusted to produce but a small anode current so that the variations of anode current of detector 7 40 will predominate to control the grid bias of detector 3.

45 Fig. 2 illustrates the effect of impressing excessive signal energy upon the detector device 7, and illustrates the advantage resulting from our invention. Curve A shows the 50 audio signal output of detector 7 of a system employing our invention plotted against the carrier frequency when the input of signal energy is controlled by the volume control. Curve B illustrates the double peak phenomenon in the tuning characteristic occurring 55 in similar systems of the prior art when an excessive amount of signal energy is impressed upon the detector. The portion of the curve B between the peaks illustrates 60 how the volume is reduced by saturation. 65

It is obvious that this phenomenon introduces distortion in the reproduced signals.

It may thus be seen that we have provided a volume control system which is simple in circuit structure and which does not involve 70 additional electron discharge devices or circuits, and which operates directly in response to any increase in the received signal energy which exceeds a predetermined energy level. Our invention has the further advantage 75 that it does not involve mechanical moving parts which introduce undesirable effects into the operation of the receiving system. Our invention has the further advantage that it automatically prevents overloading 80 the detector, thereby preventing the introduction of distortion.

While we have shown and described our invention with particular reference to certain specific receiving circuits, it will be apparent that it is not so limited and that it may be applied to other circuits as well. It will also be apparent that the principles herein disclosed are susceptible of numerous other applications, and that modifications 85 may be made in the circuit arrangements and the instrumentalities employed without departing from the spirit and scope of our invention as set forth in the appended claims. 90

What we claim as new and desire to secure by Letters Patent of the United States is:

1. In a radio receiving circuit, the combination including a heterodyne detector of the electron discharge type, and a second electron discharge detector, said detectors including cathode, anode and control elements, connections whereby current having amplitude variations dependent upon the characteristics of the transmission medium are supplied to said detectors, and means common to the cathode-anode circuits of both said detectors arranged to produce a source of direct current potential which is variable in response to the intensity of the received current and for supplying said potential to the control element of said heterodyne detector thereby to control the output thereof in response to the intensity of the received current. 100

2. A high frequency receiving circuit including an electron discharge device, a high frequency amplifier, an electron discharge detector, said electron discharge device and said electron discharge detector each including a cathode, an anode and a control element and connections whereby currents of different intensity are supplied to said electron discharge device, amplifier and detector, and means arranged in the cathode-anode circuits of said electron discharge device and said detector to produce a direct current potential which is variable in response to the intensity of the supplied current, and connections for impressing said direct current 110 115 120 125 130

potential on the control element of said electron discharge device thereby to maintain substantially constant the output of said receiving circuit.

5 3. In a radio receiving circuit, the combination of a heterodyne detector comprising an electron discharge device, a second electron discharge detector, said detectors each including a cathode, an anode and a grid element, connections whereby currents of different intensity are supplied to said detectors, a plurality of means connected in the cathode-anode circuits of said detectors for producing different direct current potentials

15

which are variable in response to the intensity of the received current supplied to said detectors, one of said means being common to the cathode-anode circuits of both said detectors, and connections for impressing 70 said different potentials upon the grid elements of said detectors whereby the direct current potential applied to said heterodyne detector operates to prevent overloading said second detector.

In witness whereof, we have hereunto set our hands.

WENDELL L. CARLSON.
RALPH S. HOLMES.
